UNITED STATES PATENT OFFICE.

LEVI F. SMITH, OF PHILADELPHIA, PENNSYLVANIA.

LOW-WATER INDICATOR.

SPECIFICATION forming part of Letters Patent No. 309,106, dated December 9, 1884.

Application filed May 8, 1884. (No model.)

To all whom it may concern:

Be it known that I, LEVI F. SMITH, a citizen of the United States, residing at Philadelphia, in the county of Philadelphia and State of Pennsylvania, have invented certain new and useful Improvements in Low-Water Indicators, of which the following is a specification, reference being had therein to the accompanying drawings.

10 My invention relates to low-water indicators, and is designed as an improvement over the device patented by me September 6, 1870, No. 107,114, and entitled "steam-indicator."

15 The object of the improvement is to provide a means for detecting any meddling or tampering with the indicator, and also to show whether or not the device is in perfect working order without lowering the water-level in the boiler.

20 In describing the improvement reference will be made to the accompanying drawings, in which Figure 1 represents an elevation, partly in section, of the indicator of former patent with the improvement attached, and 25 Fig. 2 a section through the improvement, detached.

A represents a straight pipe adapted to be screwed into a boiler, and is continued for a short distance therein, and there adapted to have screwed on it an additional pipe of any desired length to extend into the water. The extension on A is shown at B.

Integral with A is a side pipe, C, having its bore separated from that through A by a diaphragm D, so placed and of such shape as to deflect the passage, so that it will open into the boiler just below the point where the pipe A screws into the said boiler, as shown at E. The end of the pipe C extends upward at right angles, as shown at F, the upper end of which is connected to A by a rod, G, perforated at H, for the reception of a part of the indicating mechanism. The end of the pipe C is provided with a screw-plug, I.

45 Through the diaphragm D is an orifice, K, having the portion entering into the passage in the pipe A formed into a valve-seat. Op-

posite this, in the outer wall of the said pipe A, is screwed a valve-cap, L, and stuffing-box L', having an internal screw-thread. Through 50 this passes a valve-stem, M, having a thread corresponding to that in the cap, and at its inner end a proper valve, N, adapted to enter the valve-seat K. The outer end of the stem is provided with an ordinary hand-wheel, O, 55 for manipulating it. Normally the steam is in the pipe C, and passes upward through the extension F to a whistle entering through the orifice E. Also, the steam-pressure in the boiler causes the water to fill the pipe A and 60 its upper connections. This was accomplished in the patent of 1870; but with the improvement consisting of the valve in the diaphragm the steam may be admitted into the pipe A, allowing the water to fall to boiler-level and 65 letting the hot steam into the expandible tube screwed into the top of the pipe A, causing the said tube to operate the whistle-valve, indicating in an instant whether or not the device is in perfect working order, as is evident. 70

Having described the device, what I claim is—

1. In a water-indicator, a perforated diaphragm separating the steam and water passages, the said perforation being normally 75 closed by a proper valve, substantially as specified.

2. In a water-indicator, the water pipe and steam-pipe formed integral with each other and separated by a perforated diaphragm, 80 and a valve closing the said perforation and operated by a threaded stem passing through a proper valve-cap in the side of the water-pipe, the said stem having on its outer end a hand-wheel, all the parts being arranged to operate substantially as and for the purpose specified. 85

In testimony whereof I affix my signature in presence of two witnesses.

LEVI F. SMITH.

Witnesses:

CHAS. D. DAVIS,
F. T. CHAPMAN.
